(57) **CLAIM**

The ornamental design for face plate for portable hard disk drive container, as shown and described.

DESCRIPTION

FIG. 1 is a top, front perspective view of a face plate for portable hard disk drive container showing my new design; FIG. 2 is a top view thereof; and, FIG. 3 is a front view thereof.

The logo is shown in broken lines in the views for illustrative purposes only and forms no part of the claimed design. When viewing the drawings, artisans should consider that the area shown inside the center circle or oval shape of the portable disk drive container cover (or front plate) shows the assignee's logo "STEALTHDRIVE" is for illustrative purposes only and not intended to be limited to such. Any particular logo is specially missing from the design claims, such that the claims cover any manufacturer or distributor's logo in the center indicated circle of such a portable hard drive face plate.
